(57) **CLAIM**

The ornamental design for a slide transfer platform, as shown and described.

DESCRIPTION

FIG. 1 is a top, left side perspective view of a slide transfer platform showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a top, left side perspective view showing the slide transfer platform in use.

The broken lines showing the lower portion of a playground side in FIG. 8 illustrate environment and form no part of the claimed design. The remaining broken lines in the drawings illustrate portions of the slide transfer platform that form no part of the claimed design.

1 Claim, 8 Drawing Sheets
